JOURNAL LUBRICATOR DEVICE

James J. Hennessy, New York, N. Y.

Application June 11, 1930. Serial No. 460,328

6 Claims. (Cl. 308—84)

My invention relates to journal lubricators and particularly to mechanical lubricators of the type adapted to be applied to the journals of railway axles and particularly to locomotive 5 axle journals. A mechanical lubricator of this type is well illustrated in Patent No. 1,704,742 issued to me March 12, 1929.

As will be understood by those skilled in the art, this type of lubricator utilizes relative movement of the axle and box to pump oil from a reservoir to the journal (or other movements of the journal may be utilized for this purpose). In order to provide for adequate pumping of the lubricant under unfavorable conditions, such 15 as cold weather, slow speeds, slight play between journal box, etc., the pump structure is usually designed so that, under more favorable conditions, a greater quantity of lubricant is pumped than is required and it is a frequent result that surplus lubricant is lost because of its 20 passage longitudinally of the journal and beyond the ends of the bearing and of the lubricating device.

The main object of my present invention is to 25 avoid this loss of surplus lubricant pumped to the journal. This object is attained by the structure illustrated in the accompanying drawing in which—

Figure 1 is a longitudinal vertical section 30 through a lubricator device applied to a journal.

Figure 2 is a top view of the subcellar of the lubricator which embodies the essential feature of my invention.

Figure 3 is an end view of the subcellar.

In Figure 1 I illustrate the axle journal 1 of a locomotive driving wheel 2, the journal carrying the usual bearing brass 3 which will support the driver box (not shown). The lubricator, which will be mounted in the box, includes a 35 body portion 4 having a lubricant reservoir or cellar 5. A subcellar 6 is yieldingly supported on the bottom wall of the body member by means of a spring 7 and includes a pump cylinder 8 adapted to receive a pump plunger 9 which 40 is actuated alternately by movement of the wheel 2 to the right and the thrust of spring 10 to the left. The pump cylinder 8 is connected to the reservoir 5 by a suitable conduit member 11 provided with check valves, the entire device 45 operating in a manner similar to that referred to in my above-mentioned patent and the same forming no part of my present invention.

The upper portion of subcellar 6 forms a substantially rectangular waste-receiving pan 12 50 having an upstanding perimetric wall including

end portions 13 adapted to engage the surface of the journal 1, the tops of the end portions 13 of the wall being curved, as indicated at 15, to fit the journal.

The bearing brass 3 is of greater length than 60 cellar 6 and near its ends is provided with transverse grooves 16 for trapping oil moving towards the end of the bearing and directing it downwardly towards the cellar. Grooves 16 are spaced farther apart than the end portions 13 of 65 the subcellar. However, the bearing 3 only extends around the upper portion of the journal and in order to prevent the longitudinal movement of oil along the lower portion of the journal, away from the subcellar, I provide a plurality of flanges 17 on the end of the subcellar 70 6. Each of these flanges is inclined outwardly at about an angle of 45° from the vertical plane of the axis of the journal and the subcellar and extends from a point adjacent the lowermost 75 portion of the journal diagonally away from the end portion 13 of the subcellar wall, the upper edge of each flange being curved to fit the journal and each flange extending lengthwise of the journal beyond the end of the bearing. 80

As the journal rotates, the oil discharged from groove 16 and running downwardly will be wiped from the journal surface by flanges 17 and directed towards the subcellar and will flow therefrom down into the cellar and, hence, back to 85 the reservoir 5.

By locating the flanges near the center line of the subcellar, their contact with the journal is better preserved since any wear on the flanges or the journal, or any reduction in size of the 90 journal from refinishing, will be compensated by the freedom of the subcellar to move upwardly under the thrust of spring 7. It will be understood that the upper edges of wall portions 13 and flanges 17 will wear to a seat on the journal. 95 Making the flanges thin as shown will facilitate their early wearing to a journal fit.

I consider it within the spirit of my invention to locate the flanges at different points on the subcellar, to incline them at different angles 100 from that shown and to arrange them otherwise than in pairs as shown. I contemplate the exclusive use of any variations in the details of my invention which come within the scope of my 105 claims.

I claim:

1. In combination, a railway journal, a bearing thereon, a journal lubricator pan having a compartment for holding lubricant distributing 110 means, and provided with an element extending

longitudinally of said pan and engaging the adjacent surface of said journal along and beyond the area of the same coming in contact with said bearing to wipe surplus oil from the 5 journal immediately beyond the edge of said bearing.

2. In combination, a railway journal, a bearing thereon, a journal lubricator pan having a compartment with upright walls for holding 10 waste for distributing oil to said journal, and an element extending outwardly from one of said walls to engage the adjacent surface of said journal abreast the longitudinal edge of the part 15 of said bearing engageable by said journal to wipe surplus oil accumulating on the journal along said edge, said element being inclined horizontally from the axis of the pan to direct surplus oil, engaged by the outer face of the flange, longitudinally of the pan towards said 20 wall.

3. In combination, a railway journal, a bearing thereon, a journal lubricator pan having a compartment with upright walls for holding waste for distributing oil to said journal, and a 25 plurality of elements diverging horizontally from an end wall of said pan and arranged to contact with the surface of said journal along and beyond the area of the same coming in contact with said bearing to wipe surplus oil accumulating 30 on the journal immediately beyond the edge of said surface.

4. In combination, a railway vehicle journal, a waste-holding pan applied to the lower surface thereof, a journal bearing carried by said 35 journal and extending along the same a greater distance than said pan and provided with one or more transverse grooves in its journal engaging face, said grooves extending circumferentially of the journal, and one or more elements 40 extending outwardly from the end of said pan and abreast of said grooves to wipe surplus oil

from said journal as it is discharged downwardly from said grooves over said journal.

5. In combination, a railway vehicle journal, a lubricating device applied to the same and including a lubricant reservoir, a pump and conduit for conveying oil to said journal, a waste-holding pan surrounding the discharge end of said conduit, a journal bearing carried on said journal and extending along the same beyond the ends of said pan and including transverse 85 oil collecting grooves in its journal engaging face, the distance from said grooves to the ends of the bearing being less than the distance from the ends of said pan to the ends of said bearing, and flanges extending from the ends of said pan beyond the vertical planes of said grooves 90 for wiping surplus oil discharged from said grooves from said journal and returning the same to said reservoir.

6. In combination, a railway vehicle axle 95 journal, a bearing thereon, a lubricating device applied to said journal and including a cellar having a lubricant reservoir, a subcellar forming a waste-holding pan having an upstanding perimetric wall the end portions of which are shaped to fit said journal, spring means supporting said subcellar in said cellar and thrusting said end portions against said journal, a pump and conduit for supplying oil from said reservoir to said journal and actuated by the relative 100 longitudinal movement of said journal and said device; said bearing brass having one or more circumferential grooves to catch oil moving towards the end of the bearing, and flanges extending diagonally outwardly from the center of one or both end portions of said wall and traversing the vertical plane or planes of said 110 groove or grooves to intercept oil discharged downwardly from said groove or grooves and return it to said cellar reservoir. 115
